UNITED STATES PATENT OFFICE

2,678,141

CLAMP FOR INDUSTRIAL TRUCKS

Delano Wight, Jr., Battle Creek, Mich., assignor
to Clark Equipment Company, Buchanan,
Mich., a corporation of Michigan

Application June 29, 1950, Serial No. 170,967

11 Claims. (Cl. 214—653)

1

My invention relates generally to load engaging means for industrial trucks and, more specifically, is directed to clamp means adapted to engage the upper horizontal projecting edge of a crate, carton, or container.

It is an object of my present invention to provide clamp means which is adapted to be mounted to the load supporting carriage of an industrial truck for engaging the upper horizontal projecting edge of a crate, carton, or container whereby the latter may be transported, stacked, and deposited by the industrial truck.

In the preferred embodiment of my invention I contemplate the provision of vertically extending main frame means adapted to be mounted to the load supporting carriage of an industrial truck transversely thereof. Mounted to and vertically above the main frame means is secondary frame means which is adapted to carry movable jaw means, which preferably comprises a pair of jaw members. Means for moving the pair of jaw members toward and away from the upper edge of the main frame means is carried by the secondary frame means and may, for example, comprise a pair of hydraulic piston and cylinder assemblies. When the projecting edge of a crate or container is disposed between the movable jaw members and the upper edge of the main frame means, the former is urged toward the latter whereby the projecting edge of the crate or container is securely clamped therebetween. The crate or container may then be raised from the ground by effecting upward movement of the load supporting carriage of the industrial truck. After the carton or container has been raised from the ground it is supported by the clamp jaws, with a portion of the downward force exerted by the weight of a load within the crate or container being taken by the main frame means, against which the crate or container is adapted to bear.

In a modified form of my present invention for accomplishing the aforementioned object, I contemplate the provision of vertically extending frame means adapted to be mounted to the load supporting carriage of an industrial truck transversely thereof. Horizontally extending fixed jaw means is secured to the frame means adjacent the upper end thereof, and horizontally extending movable jaw means, carried by the frame means, is disposed vertically below the fixed jaw means. Means for moving the movable jaw means toward and away from the fixed jaw means is carried by the frame means and may, for example, comprise a hydraulic piston and

5 means and the carton or container raised from the ground, the latter is supported by the clamp jaw means, with a portion of the downward force exerted by the weight of a load within the crate or container being taken by the frame means, against which the crate or container is adapted to bear.

10 It is another object of my present invention to provide bearing support for a crate or container, engaged by the fixed and movable jaw means, laterally outwardly of the sides of the frame means.

15 I propose to accomplish this object by slidably mounting load engaging frame members to the frame means, adjacent each side thereof, along the lower edge thereof. It will thus be realized that when the load engaging frame members are spread laterally outwardly of the frame means that improved bearing support is provided for a crate or container which is of greater transverse extent than the frame means.

20 Now, in order to acquaint those skilled in the art with the manner of constructing and using the devices of my present invention, I shall describe, in connection with the accompanying drawings, certain preferred forms of my invention.

25 In the drawings:

Figure 1 is a perspective view of an industrial truck to which, at the forward end thereof, is secured the preferred form of clamp construction of my present invention;

Figure 2 is a front view of the clamp construction of Figure 1;

Figure 3 is a side elevational view of the clamp construction of Figure 1;

Figure 4 is a front view of a modified form of clamp construction of my present invention;

Figure 5 is a side elevational view of the clamp construction of Figure 4;

Figure 6 is a front view of another modified form of clamp construction of my present invention;

Figure 7 is a side elevational view of the clamp construction of Figure 6; and

Figure 8 is a front view of a pair of clamp constructions, of the form shown in Figure 6, disposed in side by side relation.

Referring now to Figures 1 through 3 of the drawings, there is shown a preferred form of clamp construction of my present invention at-

2

cylinder assembly preferably disposed within the confines of the frame means. After the projecting edge of a crate or container has been clamped between the fixed and movable jaw means and the carton or container raised from the ground, the latter is supported by the clamp jaw means, with a portion of the downward force exerted by the weight of a load within the crate or container being taken by the frame means, against which the crate or container is adapted to bear.

It is another object of my present invention to provide bearing support for a crate or container, engaged by the fixed and movable jaw means, laterally outwardly of the sides of the frame means.

I propose to accomplish this object by slidably mounting load engaging frame members to the frame means, adjacent each side thereof, along the lower edge thereof. It will thus be realized that when the load engaging frame members are spread laterally outwardly of the frame means that improved bearing support is provided for a crate or container which is of greater transverse extent than the frame means.

Now, in order to acquaint those skilled in the art with the manner of constructing and using the devices of my present invention, I shall describe, in connection with the accompanying drawings, certain preferred forms of my invention.

In the drawings:

Figure 1 is a perspective view of an industrial truck to which, at the forward end thereof, is secured the preferred form of clamp construction of my present invention;

Figure 2 is a front view of the clamp construction of Figure 1;

Figure 3 is a side elevational view of the clamp construction of Figure 1;

Figure 4 is a front view of a modified form of clamp construction of my present invention;

Figure 5 is a side elevational view of the clamp construction of Figure 4;

Figure 6 is a front view of another modified form of clamp construction of my present invention;

Figure 7 is a side elevational view of the clamp construction of Figure 6; and

Figure 8 is a front view of a pair of clamp constructions, of the form shown in Figure 6, disposed in side by side relation.

Referring now to Figures 1 through 3 of the drawings, there is shown a preferred form of clamp construction of my present invention at-

tached to an industrial truck, indicated generally by the reference numeral 10, having forward driving wheels 11 and rear steering wheels 12. A steering column 13, including a hand steering wheel 14, is provided adjacent the forward end of the truck 10 and is adapted to be manipulated by an operator of the truck for steering the latter. The truck 10 is powered by a suitable prime mover, as, for example, an electric motor (not shown) having suitable connection, through drive means (not shown), to the forward driving wheels 11. A conventional foot brake pedal is indicated at 15. Suitable control levers are provided at 16 and 17 for effecting operation of the various devices of the industrial truck 10.

Pivottally mounted adjacent the forward end of the truck 10, about an axis extending transversely thereof, is a substantially vertically extending conventional mast, indicated generally at 18, comprising two pairs of vertically extending channel members of which only the outer pair 19-19 are readily discernible in Figure 1. Interconnecting the upper ends of the channel members 19-19 is a crosshead 20 which supports a pair of spaced apart sprocket gears 21-21, over which chains 22-22 are trained. The chains 22-22 are secured at their one ends to a cross brace member 23 interconnecting the inner channel members of the mast 18. The other ends of the chains 22-22 are secured to a conventional load supporting carriage (not shown), mounted for vertical movement within the mast 18.

Suitably secured to the load supporting carriage is a vertically extending plate member 25. Attached to the plate member 25 is a preferred form of clamp mechanism of my present invention. The clamp mechanism comprises a vertically extending plate member 26 having a vertical plate member 27 of shorter lengthwise extent secured to the upper edge thereof in the same plane. The plate 27 has a pair of vertically extending openings 27a formed therein for a purpose to be hereinafter described. A vertically extending bar 28 is suitably secured, as by welding, adjacent its lower end to the upper edge of the plate member 27, intermediate of the ends thereof. Secured, as by welding, intermediate of its ends, to the upper edge of the vertical bar 28 is a horizontal crossbar 29 which lies in the same plane as plate members 26 and 27. Interconnecting the respective ends of plate member 27 and crossbar 29 are a pair of vertical angle members 30 and 31.

The aforescribed frame construction of the clamp mechanism is secured to the vertically extending plate member 25, carried by the load supporting carriage of the truck 10, by means of inverted hook-shaped bracket members 32, which are disposed in engagement with the upper edge of the plate member 25. The clamp frame construction is also mounted to the plate member 25 by means of upturned hook-shaped bracket members 33 which are disposed in engagement with the lower edge of the plate member 25. The upper bracket members 32 are suitably secured to the plate member 27, as by welding, while the lower bracket members 33 are detachably mounted to the plate member 26 by means of bolts 33a. From the foregoing description it will be realized that the clamp construction of my present invention may be easily and speedily secured to or detached from the plate member 25, in order that other load engaging devices may be mounted thereto.

Suitably secured to the forward surface of the

plate member 26, adjacent the upper and lower ends thereof, are a pair of horizontally extending parallel spaced apart bar members 35 and 36. The bar members 35 and 36 provide a support for a substantially vertically extending load engaging sheet member or platen 37, which is secured thereto by means of a plurality of bolts 38.

Mounted to the forward vertical surface of the horizontal crossbar 29, adjacent each end thereof, are a pair of bracket members 40 and 41, to which, respectively, are pivotally mounted, about pins 40a and 41a, the closed ends of cylinders 44 and 45 of a pair of vertically downwardly extending hydraulic piston and cylinder assemblies 42 and 43. The outer end of the piston rod 46 of the hydraulic piston and cylinder assembly 42 is pivotally mounted, by a pin member 54, between block members 48 and 52, and the outer end of the piston rod 47 of the hydraulic piston and cylinder assembly 43 is pivotally mounted, by a pin member 55, between block members 49 and 53. The block members 52 and 53 are suitably secured to the upper edges of a pair of clamp elements or jaws 50 and 51. The block members 48 and 49 are disposed in the aforescribed openings 27a in the plate member 27 for guiding vertical movement of the clamp jaws 50 and 51.

Suitable fluid lines 56, leading from a hydraulic fluid pump (not shown), carried by the industrial truck 10, are connected to the upper ends of the cylinders 44 and 45 of the hydraulic piston and cylinder assemblies 42 and 43. A second pair of fluid lines 57, leading from the hydraulic fluid pump, are connected to the lower ends of the cylinders 44 and 45. The control lever 17 is interconnected between the hydraulic fluid pump and the fluid lines 56 and 57 for permitting the operator of the truck 10 to selectively admit fluid either to the upper ends of the hydraulic piston and cylinder assemblies 42 and 43 or to the lower ends of the cylinders 44 and 45. When fluid under pressure is admitted through the fluid lines 56 to the upper ends of the cylinders 44 and 45, the piston rods 46 and 47, and their respective jaw members 50 and 51, are extended downwardly into engagement with the fixed clamp element or jaw member 35. When fluid under pressure is admitted to the lower ends of the cylinders 44 and 45, through lines 57, and lines 56 are bled, the piston rods 46 and 47, together with their respective clamp jaws 50 and 51, are retracted upwardly away from engagement with the fixed jaw member 35.

The clamping device described above is particularly adapted for engaging a lip or leading edge of a cardboard container provided along one side, adjacent the upper horizontal edge thereof. My present clamp construction obviates the necessity of stacking cardboard containers, filled with goods, on top of pallets in order that they may be transported by an industrial truck, and further renders unnecessary the use of conventional forwardly extending fork members.

When a load is gripped between the clamp elements 50 and 51 and clamp element 35, the load bears against the load engaging sheet member 37. It will be understood that other forms of load engaging surfaces may be utilized so long as the surface prevents rocking movement of the load when in gripped position.

In the use of the clamping device of my present invention, the truck 10 is lined up directly in front of a container having a laterally projecting lip or leading edge. The operator then operates the control lever at 17, effecting ad-

mission of fluid under pressure to the lower ends of the cylinders 44 and 45, through hose lines 57, which urges the piston rods 46 and 47 upwardly, together with the jaw members 50 and 51. Then the plate member 25, together with the clamp construction, is adjusted vertically within the mast 18 until the opening between the movable jaw members 50 and 51, and the fixed jaw member 35 is substantially in alignment with the protruding lip member on the container to be picked up. The truck 10 is then driven forward until the protruding lip member on the container is disposed between the movable jaws 50 and 51 and the fixed jaw member 35. The operator then manipulates the control lever 17 and places lines 57 under bleed and lines 56 under pressure, which admits fluid to the upper ends of the cylinders 44 and 45, urging the piston rods 46 and 47 downwardly, together with clamp jaws 50 and 51. The downward force exerted on the clamp jaws 50 and 51 firmly clamps the protruding edge of the container between the movable jaws 50 and 51 and the fixed jaw member 35. The plate member 25, together with the clamping mechanism and load, may then be raised within the mast and the truck driven away to the location in which the containers are to be deposited. Then the reverse procedure, as outlined above, is followed. That is, the truck is maneuvered until the container is in the desired location. Then the plate member 25, together with the clamping mechanism and load, is lowered until the container contacts the ground. The operator then manipulates the control lever at 17, placing the lines 56 under bleed and admitting fluid under pressure, through lines 57, to the lower ends of the cylinders 44 and 45, causing the piston rods 46 and 47, together with the clamp jaws 50 and 51, to retract upwardly, thereby releasing the protruding lip of the container from between the movable jaw members 50 and 51 and the fixed jaw member 35.

While, in the above description, the clamp construction of my present invention has been described as engaging and supporting a single container, it will be realized that an entire tier of containers, if within the weight supporting capacity of the truck, may be transported by clamping the leading edge of the lowermost container between the movable clamp jaws 50 and 51 and the fixed jaw member 35.

Referring now to Figures 4 and 5, there is shown a modified form of clamp mechanism of my present invention. This form of my invention, like the preferred embodiment described above, is adapted to be secured to the load supporting carriage of the industrial truck 10. The clamp mechanism comprises a vertical transversely extending plate member 70 to which, at the rear surface thereof, is secured a supporting plate member 71. The plate member 71 has secured to its rear surface a pair of spaced apart inverted hook-shaped bracket members 72 which are adapted to be disposed over the upper edge of a transversely extending frame member carried by the load supporting carriage of the industrial truck 10. Secured along the lower edge of the rear surface of plate member 71, as by bolts 74, are a pair of spaced apart upwardly extending hook-shaped support bracket members 73. The bracket members 73 are adapted to be disposed in engagement with the lower edge of the transversely extending frame member carried by the load supporting carriage of the truck 10.

Suitably secured along the upper edge of the 75 surface thereof, is secured a supporting plate

plate member 70 is a horizontally extending fixed clamp element or jaw member 75. Secured to the front surface of the plate member 70, adjacent each side thereof, are a pair of vertically extending forwardly projecting strap members 77. Interconnecting the forward edges of the strap members 77 is a load engaging plate member 78 which is secured to the strap members 77 by a plurality of screws 78a. Openings 95 are formed in the plate member 78 forwardly of bolts 74, in order that access may be had to the latter for removing the brackets 73 should it become necessary to remove the clamp construction from the truck 10.

Pivottally mounted to the forward surface of the plate member 70, adjacent the lower end thereof, centrally of the sides thereof, as by a mounting shaft 79, is the lower end of a cylinder 80 of a hydraulic piston and cylinder assembly, indicated generally by the reference numeral 81. The hydraulic piston and cylinder assembly 81 has a piston rod 82 which is adapted to be extended and retracted vertically. The upper end of the piston rod 82 is flexibly mounted within 25 a transversely extending movable clamp element or jaw member 85, which is adapted to be moved toward and away from the fixed upper jaw member 75. A slot 86 is formed in the plate member 70 and a bolt 84 is disposed therethrough, and threaded into the movable jaw 85, for guiding the latter in vertical movement. In order to maintain the lower jaw member 85 parallel to the fixed jaw 75, a guide pin 87 is mounted in the lower jaw member 85 below the bolt 84. The 30 guide pin 87 is adapted to project into the vertical slot 86 formed in the plate member 79. The guide pin 87, like the bolt 84, is adapted to slide vertically within the slot 86 when the piston rod 82 is extended or retracted.

40 The rear supporting plate 71 has a U-shaped cutout 90, adjacent the upper end thereof, which cutout 90 is provided for receiving the head of bolt 84 when the movable jaw 85 is in its retracted position, as shown by dotted lines in Figure 5.

45 A pair of openings 91 are formed in the plate member 70 adjacent each side of the hydraulic piston and cylinder assembly 81. Fluid hose lines (not shown) are adapted to be disposed through the openings 91 for connecting the hydraulic piston and cylinder assembly 81 with a source of fluid under pressure.

The mating surfaces of the fixed and movable jaw members 75 and 85 are adapted for engaging the leading edges or lips of cardboard containers. 55 It will be understood, however, that the clamp construction of my present invention is also adapted for gripping the projecting edges of other forms of containers, as, for example, the end boards of wooden crates.

60 When the leading edge of a container is gripped between the fixed and movable jaws 75 and 85 of the clamp construction, the vertically extending side of the container, adjacent the clamp construction, is adapted to bear or rest against the plate member 78.

Referring now to Figures 6 and 7, there is shown another modified form of the clamping mechanism of my present invention. This form of my invention, like the previous forms described, is adapted to be secured to the load supporting carriage of the industrial truck 10. The clamping mechanism comprises a vertical transversely extending plate 170 to which, at the rear

surface thereof, is secured a supporting plate

member 171. The plate member 171 has secured to its rear surface a pair of spaced apart inverted hook-shaped bracket members 172 which are adapted to be disposed over the upper edge of a transversely extending frame member carried by the load supporting carriage of the industrial truck 10. Secured along the lower edge of the rear surface of plate member 171, as by bolts 174, are a pair of spaced apart upwardly extending hook-shaped bracket members 173. The bracket members 173 are adapted to be disposed in engagement with the lower edge of the transversely extending frame member carried by the load supporting carriage of the truck 10.

Suitably secured along the upper edge of the forward surface of plate member 170 is a horizontally extending fixed clamp element or jaw member 175. Secured to the front surface of the plate member 170, adjacent each side thereof, are a pair of vertically extending forwardly projecting strap members 177. The strap members 177 terminate short of the bottom of the plate member 170. Interconnecting the forward edges of the strap members 177, adjacent the lower end thereof, is a load engaging plate member 178 which is secured to the strap members 177 by a plurality of screws 178a. Openings 174a are formed in the plate member 178 forwardly of the bolts 174 in order that access may be had to the latter for removing the brackets 173 should it become necessary to remove the clamp construction from the truck 10.

Pivottally mounted to the forward surface of the plate member 170, adjacent the lower end thereof, centrally of the sides thereof, as by a mounting shaft 179, is the lower end of a cylinder 180 of a hydraulic piston and cylinder assembly, indicated generally by the reference numeral 181. The hydraulic piston and cylinder assembly 181 has a piston rod 182 which is adapted to be extended and retracted vertically. The upper end of the piston rod 182 is flexibly mounted within a support block 183, which block 183 is secured, as by a bolt 184, to a transversely extending angle member 185. The angle member 185 is the lower movable clamp element or jaw member of the clamping device of my present invention, and is adapted to be moved toward and away from the fixed upper jaw member 175. A vertical slot 186 is formed in the plate member 170 and the bolt 184, provided for securing the support block 183 to the lower jaw member 185, is disposed therethrough for guiding the lower jaw member 185 in vertical movement. In order to maintain the lower jaw member 185 at right angles, with respect to the support block member 183, and parallel to fixed jaw 175, a guide pin 187 is mounted in the support block 183 and the lower jaw member 185 below the bolt 184. The guide pin 187 is adapted to project into the vertical slot 186 formed in the plate member 170. The guide pin 187, like the bolt 184, is adapted to slide vertically within the slot 186 when the piston rod 183 is extended or retracted.

The rear supporting plate 171 has a U-shaped cutout 190 adjacent the upper end thereof, which cutout 190 is provided for receiving the head of bolt 184 when the movable jaw 185 is in its retracted position, as shown by dotted lines in Figure 7.

A pair of openings 191 are formed in the plate member 170 adjacent each side of the hydraulic piston and cylinder assembly 181. Fluid hose lines (not shown) are adapted to be disposed through the openings 191 for connecting the hy-

draulic piston and cylinder assembly 181 with a source of fluid under pressure.

A pair of load engaging frame members 195 are disposed along the lower edges of the plate member 170, one adjacent each side thereof. Each of the frame members 195 has a transversely extending slot 196 formed therein. The frame members 195 are supported by means of a pair of spaced bolts 197 which are disposed through the slots 196 and are threaded into the plate member 170. It will be observed that the frame members 195 may be spread laterally by sliding the brackets 195 along the bolts 197 and may be fixed in any desired location by tightening the nuts 197.

Each of the frame members 195 is formed with forwardly projecting portions 198 adjacent the outer ends thereof, at the upper and lower portions thereof. The forward surfaces of the projecting portions 198 are adapted to lie substantially flush with the plate member 178.

The mating surfaces of the fixed and movable jaw members 175 and 185 are cross scored or serrated and are particularly adapted for engaging the leading edges or lips of cardboard containers. It will be understood, however, that the clamp construction is also adapted for gripping the projecting edges of other forms of containers, as, for example, the end boards of wooden crates.

When the leading edge of a container is gripped between the fixed and movable jaws 175 and 185 of the clamp construction, the vertically extending side of the container, adjacent the clamp construction, is adapted to bear or rest against the plate member 178 and the forwardly projecting portions 198 of the laterally slidable frame members 195. By laterally adjusting the brackets 195 containers of various widths may be engaged and supported adequately by the clamp construction of my present invention, since the containers may, if necessary, be braced at points lying laterally outwardly of the plate member 178.

As shown in Figure 8, a pair of clamp constructions, of the type illustrated in Figures 6 and 7, may be mounted to the truck in side by side relation, thereby providing a larger gripping and supporting area which, in turn, provides increased load engaging capacity. It will also be observed that the outermost frame members 195 may still be spread laterally for supporting a container at points lying laterally outwardly of the plate members 178.

While I have shown and described what I believe to be certain preferred embodiments of my present invention, it will be understood that various modifications and rearrangements may be made therein without departing from the spirit and scope of my present invention.

I claim:

1. For use with an industrial truck having a mast and a load supporting carriage movable therealong, load engaging means comprising, vertically extending frame means adapted to be mounted to the load supporting carriage transversely thereof, a fixed clamp element being secured to said frame means adjacent the upper edge thereof, movable clamp means disposed vertically below said fixed clamp element and being carried by said frame means, means carried by said frame means for moving said movable clamp means in a vertical plane toward and away from said fixed clamp element for clamping the upper edge of a load therebetween, and

said frame means having a substantially vertical load engaging surface for preventing rocking movement of a load gripped between said clamp means and said clamp element.

2. For use with an industrial truck having a mast and a load supporting carriage movable therealong, load engaging means comprising, vertically extending main frame means adapted to be mounted to the load supporting carriage transversely thereof, vertically extending secondary frame means mounted to said main frame means vertically thereabove, movable clamp means carried by said secondary frame means, means carried by said secondary frame means for moving said movable clamp means in a vertical plane toward and away from the upper edge of said main frame means for clamping the upper edge of a load therebetween, and said frame means having a substantially vertical load engaging surface for preventing rocking movement of a load gripped between said clamp means and the upper edge of said main frame means.

3. For use with an industrial truck having a mast and a load supporting carriage movable therealong, load engaging means comprising, vertically extending main frame means adapted to be mounted to the load supporting carriage transversely thereof, vertically extending secondary frame means mounted to said main frame means vertically thereabove, a pair of movable clamp elements carried by said secondary frame means, and means carried by said secondary frame means for moving said pair of clamp elements toward and away from the upper edge of said main frame means.

4. The combination of claim 3 wherein said last named means comprises a pair of hydraulic piston and cylinder assemblies.

5. For use with an industrial truck having a mast and a load supporting carriage movable therealong, load engaging means comprising, vertically extending frame means adapted to be mounted to the load supporting carriage transversely thereof, horizontally extending fixed clamp means secured to said frame means adjacent the upper edge thereof, horizontally extending movable clamp means disposed vertically below said fixed clamp means and being carried by said frame means, means for effecting movement of said movable clamp means toward and away from said fixed clamp means in a vertical plane for clamping the upper edge of a load therebetween, said last named means being carried by said frame means within the confines thereof, and said frame means having a substantially vertical load engaging surface for preventing rocking movement of a load gripped between said movable clamp means and said fixed clamp means.

6. The combination of claim 5 wherein said last named means comprises a hydraulic piston and cylinder assembly.

7. The combination of claim 5 including laterally shiftable load engaging frame members slidably mounted to said frame means adjacent each side thereof along the lower edge thereof for engaging a load laterally outwardly of the sides of said frame means.

8. For use with an industrial truck having a mast and a load supporting carriage movable therealong, load engaging means comprising, vertically extending frame means adapted to be mounted to the load supporting carriage transversely thereof, said frame means defining a

horizontal fixed clamp element adjacent its upper edge, vertically movable clamp means carried by said frame means, vertically extending means carried by said frame means for moving said movable clamp means in a vertical plane toward and away from said fixed clamp element for clamping the upper edge of a load therebetween, and said frame means having a substantially vertical load engaging surface depending from said clamp element for preventing rocking movement of a load gripped between said clamp means and said clamp element.

9. For use with an industrial truck having a mast and a load supporting carriage movable therealong, load engaging means comprising, vertically extending frame means adapted to be mounted to the load supporting carriage transversely thereof, said frame means defining a fixed clamp element adjacent its upper end, vertically movable clamp means carried by said frame means, means carried by said frame means for moving said movable clamp means in a vertical plane toward and away from said fixed clamp element for clamping the upper edge of a load therebetween, the mating surfaces of said clamp element and said clamp means extending transversely of the truck, and said frame means having a substantially vertical load engaging surface for preventing rocking movement of a load gripped between said clamp means and said clamp element.

10. For use with an industrial truck having a mast and a load supporting carriage movable therealong, load engaging means comprising, vertically extending frame means adapted to be mounted to the load supporting carriage transversely thereof, said frame means defining a fixed clamp element adjacent its upper end, upwardly and downwardly movable clamp means carried by said frame means, means carried by said frame means for moving said movable clamp means toward and away from said fixed clamp element for clamping the flap of a load which projects away from the load and extends transversely of the truck therebetween, the mating planar surfaces of said clamp element and said clamp means extending transversely of the truck, and said frame means having a substantially vertical load engaging surface for preventing rocking movement of a load gripped between said clamp means and said clamp element.

11. The combination of claim 10 wherein said means for moving said movable clamp means toward and away from said fixed clamp element comprises vertically extending hydraulic piston and cylinder means.
